UNITED STATES PATENT OFFICE

94,921

DESIGN FOR A BOTTLE

William A. Nester, East St. Louis, Ill., assignor
to Obear-Nester Glass Company, St. Louis, Mo.,
a corporation of Missouri

Application January 9, 1935, Serial No. 54,776

Term of patent 14 years

To all whom it may concern:

Be it known that I, William A. Nester, a citizen of the United States, residing at East St. Louis, in the county of St. Clair and State of Illinois, have invented a new, original, and ornamental Design for a Bottle, of which the following is a specification, reference being had to the accompanying drawing, forming part thereof.

Fig. 1 is a plan view of a bottle embodying my new design;

Fig. 2 is an elevation showing one side, both sides being identical; and

Fig. 3 is an elevation showing one end, both ends being identical.

I claim:

The ornamental design for a bottle as shown and described.

WILLIAM A. NESTER.
